Term of patent 14 years
(Cl. D58—17)

FIG. 1

FIG. 2

FIG. 3

FIG. 5

FIG. 4

FIGURE 1 is a front elevational view of my pressurized can showing my new design.

FIGURE 2 is a side elevation thereof.

FIGURE 3 is a partial rear elevation thereof.

FIGURE 4 is a top plan view thereof.

FIGURE 5 is a partial perspective side view thereof.

The essential features of my design reside in the combination of the cylindrical pressure can disclosed and the particularly formed depressed top having a conforming actuator button situated therein substantially as shown.

This application is a continuation of application Serial No. D. 65,211, filed May 17, 1961, now abandoned.

I claim:

The ornamental design for a pressurized can, substantially as shown and described.
